JEWELRY BOX

Filed Nov. 25, 1950

FIG 1

FIG 3

INVENTOR:

P. J. Kully

UNITED STATES PATENT OFFICE

163,953

JEWELRY BOX

Paul J. Kully, Edmonton, Alberta, Canada

Application November 25, 1950, Serial No. 13,125

Term of patent 14 years

(Cl. D58—12.6)

To all whom it may concern:

Be it known that I, Paul J. Kully, a citizen of the Dominion of Canada, residing at Edmonton, Province of Alberta, have invented a new, original, and ornamental Design for Jewelry Box, of which the following is a specification, reference being had to the accompanying drawings, forming a part hereof, in which

I claim:

The ornamental design for a jewelry box, as shown.

PAUL J. KULLY.
